UNITED STATES PATENT OFFICE.

WILLIAM ATTILIO BRUNO, OF ASTORIA, NEW YORK.

ELECTRIC COIL AND INDUCTANCE.

Application filed April 24, 1925. Serial No. 25,625.

- My invention relates to inductances especially adaptable to radio frequency circuits, as either tuning units or radio frequency transformers and is of particular 5 importance when used in connection with multi-stage tuned radio frequency amplifiers in which it is necessary to employ a plurality of inductances or radio frequency transformers, it being especially desirable 10 that each inductance or radio frequency transformer be uniform as to their electrical characteristics, so as to result in the maximum electrical efficiency and selectively of 15 the circuit.
- Its objects are to provide an inductance or radio frequency transformer of a type having the highest electrical efficiency possible, and maximum elimination of absorption 20 losses.
- I obtain these results by so construction and arranging the inductances or their supports or mountings, so as to practically 25 eliminate the defects of inductances commonly used heretofore. Such defects involve functional deficiencies referred to as 30 "losses" which are due to distributed capacity inherent in most types of inductances.
- Current losses are principally caused by 35 the presence of foreign conducting bodies in the vicinity of the electrical field of the inductance itself, and also to dielectric absorption losses due in a large part to the improper arrangement of the dielectric in contact with or adjacent to the inductances.
- Another object of my invention is to provide 40 an improved method of assembling the tickler or feed back coil, thereby providing a minute control of regeneration in such a circuit.
- These and other objects of my invention are set forth in the following description and references hereby made to the accompanying drawings, in which similar numerals of designation refer to similar parts 45 throughout the several views.
- Fig. 1, is an elevation of a tuning inductance embodying my invention.
- Fig. 2, is a section taken on line 2—2 of Fig. 1.
- Fig. 3, is an enlarged section taken on line 3—3 of Fig. 4, and shows details of construction.
- Fig. 4, is a vertical section taken on line 4—4 of Fig. 5, but with the primary and 55 secondary windings omitted for the sake of clearness.
- Fig. 5, is a top view of the tuning inductance of which Fig. 4 is a vertical section taken on line 4—4 of Fig. 5, with the tickler inductance in the position of maximum coupling.
- A preferred form of my invention is the inductance unit shown in Fig. 1, commonly known as a three-circuit "tuner" having a polygon coil shape and comprising three inductance coils, a secondary winding 1^a, primary winding 4, and the third or tickler winding 10, which is shown in detail in Figs. 4 and 5.
- The polygon coil shape is formed by the 70 end rings 7—7 which are preferably of hard rubber or other good insulating material having holes drilled and positioned at equal distances to accommodate the glass rods 8, and binding posts or terminals 2, 3, 5, 6, 18, 75 and 19, constructed and assembled as shown in Figs. 1 to 5.
- It will be noted by the construction shown that I eliminate the use of solid cylinders, and in an electric coil or inductance of my 80 construction, because of the skeleton coil shape employed and especially the use of glass supports which form a part of the coil shape or form, and accommodate the windings forming the coil or coils, I am able to 85 produce an inductance having comparable electrical characteristics to that of an air core or self-supporting coil employing no coil form, which type of construction could not be carried out practically in a three-circuit tuning inductance due to the necessity of providing a structure to accommodate the third 90 inductance or tickler winding 10.
- For the purpose of controlling the amount 95 of coupling between the secondary inductance 1^a, and tickler coil 10, the latter is mounted upon a movable shaft on which I have provided an insulated section 11, for the purpose of keeping dielectric losses to a minimum. This movable inductance or coil 100 10, consists of a number of turns of copper wire wound in a spiral between insulated sections of shaft or tubing 11, which is slotted along part of its entire length.
- An extension 12, is inserted in the insulating shaft 11, and is secured to it by a machine screw or pin 13. In order to prevent 105 accidental moving of the inductance or coil 10, or from revolving of its own accord, I have provided a spring 15, on shaft 12, positioned between shoulder of insulating member 11, and metal bracket 16. This pro-

duces an even pressure upon said shaft, thereby preventing accidental moving or revolving of its own accord of the inductance or coil 10.

5 Fig. 3, shows a constructional detail in which screw 13, is positioned on shaft 12 in relation to inductance or coil 10, so as to provide a stop to prevent a continuous revolving of inductance or coil 10 in either 10 direction so as to insure a non-breaking of coil terminals 28 and 29.

In Fig. 3, is shown how the inductance or coil leads 28 and 29, are brought to terminals 18 and 19, through insulating shaft or 15 tube 11, and hole in ring 7, forming the bearing for said insulating shaft or tube 11.

I claim and desire to protect by Letters Patent:

1. An electric coil or inductance of the 20 type described comprising a set of windings, vertical supports, two end rings of dielectric or insulating material in which there are an even number of recesses evenly spaced to accommodate said vertical supports, assembled 25 to form a polygon, a reinforcement band of dielectric material disposed intermediate said supports, and a shaft comprising

ing a section of dielectric material slotted for part of its length, a spiral inductance winding, secured to said shaft, said shaft 30 having a metallic extension secured by suitable means and rotatably mounted in end ring of dielectric material.

2. An electric coil or inductance of the type described comprising a set of windings, 35 vertical supports, two end rings of dielectric or insulating material in which there are an even number of recesses evenly spaced to accommodate said vertical supports, assembled to form a polygon, a reinforcement band of dielectric material disposed intermediate said supports, and a shaft having a section of dielectric material slotted for part of its length 40 with a metallic extension secured to it by suitable means, a mounting bracket member, 45 a spiral spring around said metal extension, one end of said spring resting against a shoulder of said insulating section, and the other end against said mounting bracket, so as to provide a tension upon said shaft. 50

Signed at New York, in the county of New York and State of New York, this twenty-first day of April, A. D. 1925.

WILLIAM ATTILIO BRUNO.
